UNITED STATES PATENT OFFICE.

FRANK JOSEPH SPROEHNLE, OF PHILADELPHIA, PENNSYLVANIA, ASSIGNOR
OF ONE-HALF TO EDWARD D. CHANINEL, OF SAME PLACE.

GASOLENE-ENGINE.

SPECIFICATION forming part of Letters Patent No. 653,971, dated July 17, 1900.

Application filed October 21, 1899. Serial No. 734,304. (No model.)

To all whom it may concern:

Be it known that I, FRANK JOSEPH SPROEHNLE, a citizen of the United States, residing in the city and county of Philadelphia, in the State of Pennsylvania, have invented a new and useful Improvement in Gasolene-Engines, which improvement is fully set forth in the following specification and accompanying drawings.

10 My invention consists of an improved construction of a gasolene-engine in which the number of parts is reduced to a minimum and provision made for manufacturing engines of this character in a cheap and effective manner.

15 It also consists of a novel construction of controlling-valve and its adjuncts, said valve being operated by suitable tripping mechanism carried by the connecting-rod of the engine, whereby the admission and ignition of the commingled air and gas or gasolene are effectively regulated.

20 It further consists of novel details of construction, all as will be hereinafter fully set forth, and particularly pointed out in the claims.

25 Figure 1 represents a transverse sectional view of a gasolene-engine embodying my invention, certain of the parts being shown in elevation. Fig. 2 represents a plan view of the engine seen in Fig. 1, showing especially the valve-operating mechanism. Fig. 3 represents a section on line $x-x$, Fig. 1. Fig. 4 represents a partial side elevation and partial vertical section of certain of the parts seen in Fig. 1, some of which, however, are in different positions from those seen in Fig. 1. Fig. 5 represents a plan view of certain of the parts seen in Fig. 4. Fig. 6 represents a 30 partial side elevation and partial vertical section of certain of the parts seen in Fig. 4. Fig. 7 represents a plan view of certain of the parts seen in Fig. 5, some of which, however, are in different positions from those seen in said Fig. 5.

40 Similar letters and numerals of reference indicate corresponding parts in the figures.

Referring to the drawings, a designates the engine, the same consisting of a cylinder b , which is surrounded by the water-jacket c ,

said cylinder containing the piston d , which has connected thereto one end of the connecting-rod e , the other end of the latter being suitably attached to the crank-pin f , which is mounted on the crank g of the shaft h , which latter carries the balance or fly wheel i . The connecting-rod e is provided with a dog j , which is adapted to contact with the portion k of the tripping member l which is pivoted upon the pin m and has the portion o carried thereby adapted to contact with the ends p of the lever q , which is fulcrumed at r , said lever being provided with the raised portion s , on which is adapted to rest the extremity t of the rod u , which is mounted in a suitable 55 guide or bearing v , said end t being in contact with said raised portion by reason of the spring w , one end of the latter contacting with said guide v and the other end thereof contacting with the pin or abutment x , carried by said rod, the action of the above parts being rendered positive by suitable springs. (Best seen in Fig. 3.) The rod u is provided with the offset portion y , to which is attached the inlet-valve plug z , the latter having the 60 port 1 therethrough, said valve being movable in a suitable seat 2 , contained in the casting 3 , into the upper portion of which latter leads a pipe 4 for conveying the gas, gasolene, or other fluid.

65 5 designates a passage leading from a point below the valve z through the port 6 , from which the gasolene is discharged into the interior of the cylinder b , the requisite quantity of air being admitted through the port 7 .

70 8 designates an air and gas valve mounted on the rod 9 and adapted to close the port 6 at proper intervals, said valve-rod carrying a head 10 , against which contacts one end of the spring 11 , the other end of the latter contacting with the adjacent portion 12 of the cylinder or cylinder-head through which the rod 9 passes.

75 13 designates an arm attached to the valve z , the lower extremity 14 of said arm being 90 adapted to contact with the rod 9 , so as to move the valve 8 to the desired extent at proper intervals, as will be explained.

80 The ignition of the charge of gas or gasolene and air is effected through the medium 100

of the electricity conveyed to the electrodes 15 and 16 by the conductors 17 and 18, respectively, the contact being closed by means of the pin or projection 19, which is attached 5 to the piston *d*, it being apparent that when said piston moves to its extreme right-hand position the projection 19 closes the circuit between said electrodes. When the said pin moves away from said electrodes, the contact 10 is broken, thereby causing the electric spark, which effects the ignition of the charge which enters through the port 6.

The operation is as follows: When the parts are in the position seen in Fig. 1, the piston 15 is advancing to the left, and the suction created thereby unseats the valve 8, and the gasoline and air enter through the passage 5 and port 7, respectively. It is to be understood that the extremity 20 of one of the projections 20 21 on the raised portion *s* is in contact with the extremity *t* of the rod *u*, as seen in Figs. 1 and 7, and that when the rod *u* is in this position it has been moved to its full extent to the right, so as to bring the port 1 in the valve- 25 plug *z* in alignment with the passage 5 in order that the gasoline may flow through said port 1, passage 5, and port 6 and enter the cylinder *b*, it being noted that when the valve- plug *z* is in the position seen in Figs. 1 and 7 30 the dog *j* is in contact with the portion *k* of the member *l* and causes the portion *o* carried by the latter to impart a partial rotation to the raised portion *s*, due to the forward movement of the connecting-rod *e*, thereby 35 turning said raised portion *s* sufficiently to bring the same into the position seen in Fig. 5, whereupon the rod *u* will be caused to slide to the left by the action of the spring *w* and to abut against one of the shoulders 22 on the 40 raised portion *s*, and thus cause the valve- plug *z* to move into the position seen in Figs. 5 and 6, whereupon the supply of gasoline to the cylinder *b* will be cut off, it being understood that the piston *d* has not as yet completed its full movement to the left. When 45 the several movable parts of the engine are in the positions seen in Figs. 2 and 4, the piston *d* has completed its movement to the left, due to the explosion in the cylinder *b*, and the raised portion *s* has been turned, as hereinbefore described, so as to cause it 50 to be in the position seen in Fig. 2, whereupon the spring *w* will still further advance the rod *u* to the left and in so doing will 55 cause the end 14 of the arm 13 to force the rod 9 to the left, as seen in Fig. 4, against the action of the spring 11, and thus open the port 6 to permit the escape of the waste products of the explosion. The momentum of 60 the wheel *i* causes the piston *b* to be moved to its full extent to the right, then to the left, and when moving in the latter direction the connecting-rod *e* will again operate the valve- plug *z*, as hereinbefore described, in order to 65 again supply the cylinder *b* with gasoline for

a subsequent explosion. It is to be noted that when the arm 13 has been moved, as hereinbefore described, from the position seen in Fig. 1 to that seen in dotted lines in the same figure the end 14 of said arm 13 will 70 occupy such a position that when the port 6 is closed by the plug 8 the head 10 of the rod 9 will be brought in contact with the end 14 of the arm 13, so that when said arm 13 completes its movement to the left it will cause 75 the plug 8 to leave its seat in the port 6 for the purpose hereinbefore described. As soon as the piston commences its return stroke to the right prior to an explosion, which occurs at every fourth stroke of the piston, the valve 80 8 is caused to seat and the charge of air and gas is compressed until the projection 15 closes the contact between the electrodes, causing the explosion, and the piston moves 85 toward the left again.

If desired, a plurality of valves 8 may be used, one serving as an inlet-valve and the other as an exhaust.

Having thus described my invention, what I claim as new, and desire to secure by Letters 90 Patent, is—

1. In a gas-engine, a cylinder, an air and gas inlet and exhaust valve controlling a port communicating with said cylinder and with an air and fuel supply, an inlet-valve controlling said fuel-supply and adapted to actuate said air and gas inlet and exhaust valve, and means for operating said inlet-valve.

2. In a gas-engine, a cylinder, an air and gas inlet and exhaust valve controlling a port 100 leading to said cylinder, a passage leading to said port, an inlet-valve controlling said passage, an arm attached to said inlet-valve and adapted to actuate said air and gas inlet and exhaust valve, and means for operating said inlet-valve.

3. In a gas-engine, a cylinder, an air and gas inlet and exhaust valve controlling a port leading to said cylinder, a passage leading to said port, an inlet-valve controlling said passage, an arm attached to said inlet-valve and adapted to actuate said air and gas inlet and exhaust valve, and means for operating said inlet-valve, the latter being actuated by the connecting-rod of the engine.

4. In a gas-engine, a cylinder, a piston therein having a connecting-rod attached thereto, a tripping member *l* having a portion *k* adapted to be hit by a dog *j* carried by said connecting-rod, a portion *o* carried by said dog, and adapted to contact with the ends *p* of the lever *q*, the latter having the raised portion *s*, a rod *u* adapted to contact therewith, a spring *w* holding said rod in position, an inlet-valve plug *z* actuated by said rod and having a port therethrough, a passage 5 controlled by said inlet-valve, a port 7 serving as an inlet and exhaust port, an air and gas inlet and exhaust port 6, a spring-actuated air and gas valve 8 controlling the latter, and an 120 125 130

arm extending from said inlet-valve plug and adapted to actuate said air and gas inlet and exhaust valve.

5. In a gas-engine, a cylinder, an inlet-valve, a passage 5 controlled thereby, a port 6 leading to said cylinder, an air and gas inlet and exhaust spring-actuated valve controlling said port, an arm 13 on said inlet-

valve for actuating said air and gas inlet and exhaust valve, and means actuated by the 10 connecting-rod for actuating said inlet-valve.
